Primary Examiner—Joel Sincavage
Assistant Examiner—Maurice Stevens(57) **CLAIM**

An ornamental design for an air flow inlet, as shown and described.

DESCRIPTION

FIG. 1 is a bottom perspective view of the air flow inlet;
FIG. 2 is a top perspective view of the air flow inlet;
FIG. 3 is a top plan view of the air flow inlet;
FIG. 4 is a rear elevation view of the air flow inlet;
FIG. 5 is a bottom plan view of the air flow inlet;
FIG. 6 is a front plan view of the air flow inlet;
FIG. 7 is a left perspective view of the air flow inlet; and,
FIG. 8 is a right perspective view of the air flow inlet.
